SPARK ARRESTER

Clarence H. Gormley, Farmington, Mo., assignor
of one-half to George A. Rickus, Farmington,
Mo.

Application June 4, 1937, Serial No. 146,338

4 Claims. (Cl. 183—52)

My invention relates to improvements in spark arresters for chimneys.

It is a well known fact that the screened spark arresters such as now used on chimneys for the purpose of preventing live sparks from blowing out onto the roof are defective in that the screen rapidly becomes clogged up with soot and prevents the free escape of the smoke with a resulting loss in draft. It is the main object of my invention to provide a spark arrester which is simple and inexpensive in construction and which includes means for keeping the screen free of soot at all times without attention from the owner.

Another object is to provide a spark arrester of this kind including a rigid center post and a drum-like screen journaled to turn freely on the post and over the chimney so that all smoke flowing from the chimney must pass through the screen, there being a wind vane attached to the screen so as to cause it to rotate around the center post as the wind changes its direction, and brackets supported by the post and carrying toothed cleaner bars which will mesh with the screen as it turns and, penetrating the screen, will keep the same from clogging up with soot.

With these and other objects in view the invention resides in the novel construction and arrangement of parts as hereinafter fully set forth and claimed, reference being had to the accompanying drawing as showing a preferred embodiment of my invention for purposes of exemplification.

In the drawing:

Figure 1 is a vertical cross section through my spark arrester as mounted on a chimney.

Figure 2 is a plan view.

Figure 3 is an enlarged fragmental perspective view of one cleaning rack and the screen.

In carrying out my invention I provide a center post 5 adapted to be supported rigidly and vertically above a chimney A in any suitable manner as by means of a mounting plate 6 to the center of which the post is secured by means of a neck 7 so that as the plate is laid flat on the top of the chimney the post will stand upright as shown. The margins 6a of the mounting plate 6 are then bent downward over the sides of the chimney and tie wires 8 are secured to ears 9 struck up from the plate and run down to a wire 10 which is secured around the chimney and holds the plate in place. Of course this mounting may be varied as necessary to fit different types of chimneys. The plate 6 has apertures 11 so that the smoke may pass freely from the chimney.

55 The spark arrester screen 12 is of cylindrical

shape made up of screen wire or other foraminous material secured at the ends 13 to upper and lower end frames 14—14a which each include the outer rim 15 and inner hub 16 connected by spokes 17. The hubs 16 are journaled freely on the center post and the whole assembly is supported against axial displacement by a hanger or bearing bracket 18 secured to the upper frame 14 and having a center aperture 19 registering with the upper end of the center post 5. A bearing ball 20 10 is seated in a socket 21 in the upper end of the center post and fitting partially into the aperture 19 supports the screen assembly while permitting it to turn freely. The center post 5 probably would be tubular and the ball 20 would rest in 15 the open upper end though of course a solid post could be used with a socket for the ball as described. The parts are so arranged that the lower end of the screen 12 just clears the mounting plate 6. A wind vane 22 is secured by brackets 20 23 to the upper frame 14 and extends radially outward from the screen so as to catch the wind and cause the screen to turn as the wind changes direction.

A pair of bracket frames is provided and formed 25 up from bar or strip material bent to provide short mounting portions 24, and outwardly turned lower arms 25 which terminate just inside the lower end of the screen 12. Upper arms 26 are extended vertically up inside the screen and spaced 30 therefrom, these arms being supported by the lateral reaches 27 and the arms terminating in radially and outwardly turned fingers 28. The mounting portions 24 are secured on opposite sides of the center post by bolts 29 to rigidly support the bracket arms in the stated positions. Baffle plates 30, 31 and 32 are supported between the upper arms 26 by ears 33 turned downwardly at their margins and secured to the arms by screws 34. The upper and lower baffles 30 and 32 40 are solid flat disks of a diameter just fitting inside the arms 26 while the center baffle 31 is larger, is notched out at 35 to clear the arms and has a large center aperture 36 which however is smaller than the upper and lower baffles. 45

It will now be understood that the smoke flowing from the chimney A will enter the screen 12 and be deflected by the baffles 30, 31 and 32 out through the screen so as to prevent the escape of any sparks. However the screen would soon become clogged with soot and the draft would be greatly reduced.

To prevent this I provide the screen cleaning means now to be described. The extremities of the arms 25 and the fingers 28 have apertures 37 55

and mounted vertically between these parts parallel to the screen 12 are the cleaning bars, racks or grates 38 which have the reduced trunnions 39 at their ends journaled in the apertures 37. These bars 38 have the rows of radially extended teeth 40 of outwardly tapering shape and square cross section which are placed in mesh with the screen. That is, the teeth 40 are arranged and provided to penetrate the spaces 41 between the wires 42 which form the screen as shown in Figure 3. Now as the screen 12 turns about the center post 5 under the influence of changing wind directions the cleaning bars 38 will be rotated and the teeth 40 will work and penetrate through the screen punching all particles of soot outward so that it falls clear of the screen. This action assures that the screen is clean at all times. Of course more than two of the cleaning bars may be used by arranging more bracket arms to support them. The actual penetration of the screen by the teeth is important since in no other way can the screen be absolutely cleaned and brushes and scrapers are ineffective since they only brush around the interior of the screen.

While I have herein set forth a certain preferred embodiment of my invention it is understood that I may vary from the same in minor structural details so as best to provide a practical device for the purposes intended, not departing from the spirit of the invention and within the scope of the appended claims.

I claim:

1. In a device of the kind described, a center post, means for mounting the same vertically atop a chimney, screen frames journaled in vertically spaced relation on the center post, a bearing bracket on the upper screen frame, a bearing ball journaled between the bracket and upper end of the center post, a cylindrical screen extended between the screen frames, upper and lower arms extended rigidly from the center post, cleaner

bars journaled vertically between these arms and extended parallel with and inside the wall of the screen, and teeth radially extended from the cleaner bars in mesh with the screen.

2. In a device of the kind described, a center post, means for mounting the same vertically atop a chimney, screen frames journaled in vertically spaced relation on the center post, a bearing bracket on the upper screen frame, a bearing ball journaled between the bracket and upper end of the center post, a cylindrical screen extended between the screen frames, upper and lower arms extended rigidly from the center post, cleaner bars journaled vertically between these arms and extended parallel with and inside the wall of the screen, teeth radially extended from the cleaner bars in mesh with the screen, and baffles extended horizontally between the said upper arms.

3. In a device of the kind described for mounting over the top of a chimney, a center post, means for mounting the post rigidly and vertically atop the chimney, a cylindrical screen journaled co-axially over the post and adapted to rotate about the same, vertically spaced frames secured rigidly to the center post within the cylindrical screen, the frames being extended laterally, cleaning bars journaled in the outer portions of the frames parallel with and inside the cylindrical walls of the screen the same being anchored against circumferential movement around the center post though rotatable upon their own axes, teeth radially extended from the cleaning bars and arranged in mesh with the apertures of the screen, and a wind vane mounted so as to rotate the screen as the vane turns with the wind, whereby the teeth of the cleaning bars automatically operate to keep the apertures of the screen open and unclogged.

4. In a structure as defined in claim 3, baffles arranged within the cylindrical screen.

CLARENCE H. GORMLEY.
